UNITED STATES PATENT OFFICE.

DOUGLAS HAIGHT, OF COSHOCOTON, OHIO.

DESIGN FOR A WEATHER-VANE.

SPECIFICATION forming part of Design No. 33,586, dated November 20, 1900.

Application filed October 26, 1900. Serial No. 34,515. Term of patent 7 years.

To all whom it may concern:

Be it known that I, DOUGLAS HAIGHT, a citizen of the United States, residing at Coshocton, in the county of Coshocton and State of Ohio, have invented and produced a new and original Design for Weather-Vanes; and I do hereby declare the following to be a full, clear, and exact description of the invention, such as will enable others skilled in the art to which it appertains to make and use the same.

The subject-matter of this invention is a design for a weather-vane, the essential feature of which is the figure of a woman posed centrally upon a horizontally-arranged arrow and having tapering blades or wings projected from the shoulders in diametrically opposite directions.

In the accompanying facsimile drawing of the design the arrow is indicated at A, the

figure of a woman at B, and the blades or wings at C and D. The arrow A in its normal position is horizontal, and the figure B is erect and located central of the arrow and full face. The blades C and D taper outwardly from the shoulders upon straight lines and project in opposite directions from a straight line passing through the shoulders.

Having thus described the invention, what is claimed as new is—

The design for a weather-vane, substantially as herein shown and described.

In testimony whereof I affix my signature in presence of two witnesses.

DOUGLAS HAIGHT. [L. s.]
